UNITED STATES PATENT OFFICE.

ISAAC B. HAMMOND, OF CHICAGO, ILLINOIS.

ORE-ROASTING FURNACE.

SPECIFICATION forming part of Letters Patent No. 404,000, dated May 28, 1889.

Application filed October 1, 1888. Serial No. 286,865. (No model.)

To all whom it may concern:

Be it known that I, ISAAC B. HAMMOND, of Chicago, in the county of Cook and State of Illinois, a citizen of the United States, have invented certain new and useful Improvements in Ore-Roasting Furnaces, of which the following is a specification.

My present invention relates to that class of furnaces particularly adapted for desulphurizing and for manufacturing sulphuric acid from ores of iron, copper, and arsenical pyrites; and it has for its object to improve these furnaces in certain details of construction.

15 Furnaces of the above-described class are shown in United States Letters Patent No. 248,521 to Peter Spence, and in English Letters Patent No. 64 of 1868 to the same inventor. In these furnaces the ore to be de-
20 sulphurized is fed upon the furnace-floor, and is there spread and gradually carried along to a point of discharge either onto a second floor or outside.

25 My present improvements relate to the mechanism for so automatically raking or spreading and discharging the ore. In these furnaces as now ordinarily constructed a tier of such floors is commonly employed, the ore being fed onto the upper one and
30 thence distributed and discharged over and upon the others successively, as shown in the American patent before cited. My improvements are applicable either to such furnaces having a plurality of floors or to a furnace
35 having a single floor, as shown in the English patent above mentioned.

In the drawings I have represented my improved raking mechanism in the form now best known to me.

40 Figure 1 is a plan view of the raking device; Fig. 2, an end elevation; Fig. 3, a side elevation thereof, and Fig. 4 a section on the line xx of Fig. 1.

It is desirable in the operation of desulphurizing that the ore should be fed into the furnace in limited quantities and at regulated intervals, and that while it is upon the floor of the furnace and subject to the heat it should be raked or stirred, and also should
45 be gradually carried across the floor to the point of discharge.

In the raking devices contained in the patents above mentioned the rake-head has had simply a reciprocating motion over the furnace-floor, the teeth of the rake being generally triangular, with the base of the triangle set toward the place where the ore is to be discharged. Two rows of these teeth have generally been used, the teeth being set in the rake-head checker-board fashion or so as to break joints. With such rakes it has been found in practice that all the ore would not be drawn or moved to the discharge-
55 office, but ore would be left at the end of the floor farthest from the discharge in gradually-increasing quantities, and would there become gradually banked up to such an extent as to require the opening of the furnace and the raking out of the banked-up ore by special devices.

70 My improved rake, to obviate this defect, is constructed with a double or two faced head, II II' , each face having teeth I I , of ordinary construction. The rake is hung by means of a cross-shaft, K , between slides L L , by which it is adapted to be moved over the furnace-floor. The rods M M , by which power is transmitted to operate the rake, are connected to the rake-head at a point outside the center of oscillation of the shaft K , preferably to a pair of gudgeons, N N , as shown, extending through slots O O in the slides L L , the ends of which slots act as stops to limit the radial motion of the gudgeons, and consequently of the swinging rake-head. 80 These slots are to be of a length sufficient to permit the rake-head to swing from the position in which one face with its teeth is in contact with the ore to that in which the teeth of the other face are similarly brought 85 in contact with the ore.

90 From this construction it will be seen that when the rake is moving in one direction the rearmost face, as H , with its teeth is in contact with the ore. When the limit of motion 95 is reached and the return motion of the rods M M commences, its first effect is to rock the rake-head and bring down the farther face, H' , into position to rake the ore, but at a point beyond the extreme range of the face 100 H and consequently beyond the ore which the teeth of the face may have carried for-

ward. The gudgeons now bringing up against the end of the slot, the rest of the motion of the rods carries the rake backward toward the discharge-orifice and causes a certain 5 portion of the ore to be discharged through the same. In this way the face of the rake which acts during its motion toward the discharge-orifice being always beyond the farthest body of ore, no portion of the latter can 10 get beyond the range of the rake in returning, and thus the banking up of the ore is prevented.

The rods M M, which for convenience are 15 duplicate, as shown, extend outwardly beyond the face of the furnace-wall and are connected with any suitable source of reciprocal in-and-out motion. This motion, which, as is well known, should be quite slow, may be 20 constant or may be intermittent—*i. e.*, the rake may remain at rest for a time after it has finished each complete course backward and forward through the furnace.

I do not wish to be understood as claiming 25 herein, broadly, raking devices for ore-furnaces, as devices for those purposes have been long known.

A rake having a two-faced swinging head is not broadly new with me, the same being shown in United States Letters Patent No. 30 80,065. In that patent, however, and in all structures heretofore used, so far as I am aware, the rake-rods are connected to the swinging head at its center of oscillation, and therefore cannot be utilized to oscillate or

swing the head. By my improvement, however, the rake-rods being connected to the swinging head at a point outside the center of its swing, I am enabled to oscillate the head by means of the rake-rods alone. I am thus enabled to dispense with the additional 40 devices for this purpose heretofore employed—as, for example, in the patent above mentioned, in which the head is oscillated by means of extensions projecting up and engaging with the end walls of the furnace. 45 By doing away with these additional parts the structure is materially simplified and improved.

I claim—

A sliding rake for ore-furnaces, having a 50 double or two faced swinging head, each face being provided with suitable teeth, the said head being pivotally connected to the rake-body, rake-rods connected to the said swinging head outside the center, around which it 55 swings, and stops, substantially as described, to limit the extent of swing of the head to bring one or the other of the rake-faces in working contact with the ore, substantially as and for the purpose set forth.

In testimony whereof I have hereunto subscribed my name this 21st day of September, A. D. 1888.

ISAAC B. HAMMOND.
